UNITED STATES PATENT OFFICE.

EDGAR M. FUNK, OF WYTHEVILLE, VIRGINIA.

MASSAGING APPARATUS.

No. 843,674.

Specification of Letters Patent.

Patented Feb. 12, 1907.

Application filed June 20, 1906. Serial No. 322,629.

To all whom it may concern:

Be it known that I, EDGAR M. FUNK, a citizen of the United States, residing at Wytheville, in the county of Wythe and State of Virginia, have invented a new and useful Massaging Apparatus, of which the following is a specification.

This invention relates to massaging apparatus; and its object is to provide a rubbing device, utilizing a vacuum for drawing the skin of the patient partly thereinto, so as to open the pores and permit undesirable secretions to be quickly and thoroughly removed.

Another object is to provide a device which is under the constant control of the operator and whereby the suction created by the vacuum can be established at will and at any period during the rubbing operation.

A still further object is to provide novel means for engaging the skin of the patient during the massaging operation, so as to thoroughly knead it and expand the pores.

With the above and other objects in view the invention consists of a head having a recess in one face, and a passage extends from this recess and communicates, through a flexible tube, with a tank in which a vacuum is adapted to be formed in any preferred manner. A valve normally closes the passage in the head and is constantly under the control of the operator, so that a suction can be established within the recess whenever desired simply by opening the valve. The head extends into a massaging-frame, having cross-bars which extend across the recess in the head, and these bars are adapted to rub the skin of the patient when the head is moved thereover, so as to spread the pores and knead the flesh. While the device is applied to the skin the suction can be established in the manner stated, so as to draw the skin between the bars of the massaging-frame and open the pores. Should the head be moved over the skin while the suction is in force, the bars will force all undesirable secretions from the pores.

The invention also consists of certain other novel features of construction and combinations of parts, which will be hereinafter more fully described, and pointed out in the claims.

In the accompanying drawings is shown the preferred form of the invention.

In said drawings, Figure 1 is a view of the complete apparatus, the head and the frame

thereon being shown in section. Fig. 2 is a perspective view of the massaging-frame, and Fig. 3 is a plan view of a modified form of massaging-frame.

Referring to the figures by characters of reference, 1 is a head having a recess 2 in one face thereof, from the inner wall of which extends a passage 3, opening through an extension 4, projecting from the head. This extension engages one end of a flexible tube 5, connected to a tank 6, and a vacuum is adapted to be formed within this tank by means of a suitable suction-pump 7. The passage 3 is intersected by an elongated recess 8, extending into the head 1 from one face thereof. A slide-valve 9 is mounted in this recess, and a spring 10 is interposed between the end of the recess and the slide-valve to hold said valve normally in position to close the passage. An opening 11 is formed within the valve, and by moving said valve inward and compressing the spring this opening will be caused to register with the passage 3. A button 12 is preferably formed at the outer end of the valve to facilitate its actuation.

A preferably rectangular massaging-frame 13 surrounds the recessed face of the head 1 and may be covered with rubber tubing 14 or any other soft material which will not injure the flesh when rubbed thereover. Parallel cross-bars 15 connect the sides of the frame. If desired, additional parallel bars 16 may connect the ends of the frame, so that a plurality of rectangular openings will be formed by the intersecting bars, as shown in Fig. 3.

In using the apparatus a vacuum is first established within the tank 6 by means of pump 7. The head 1 is then inserted into the frame 13, which will fit tightly thereon by reason of the rubber covering 14, which is provided. After the parts have been prepared in this manner the frame 13 is rubbed over the skin of the patient and the bars 15 will knead the flesh and open or expand the pores. After this operation has been carried a desired period the valve 9 is pressed inward, so as to open the passage 3, and a suction is promptly established within the recess 2. This will result in the skin being drawn between the bars 15, and by continuing the movement of the frame under these conditions any secretions within the pores will be quickly removed therefrom. The flexible covering 14 serves not only to prevent injury

to the patient, but also seals the recess 2 in order that the suction may be readily produced. By utilizing intersecting bars 15 and 16 the frame can be moved in any direction with the same results, and a pinching effect will be produced upon the skin by moving it diagonally, because the skin will become wedged in the angles formed by said bars.

10. It will be seen that this apparatus is very simple in construction and is very effective in that a suction is utilized in lieu of mechanical means ordinarily employed for the purpose of holding the pores open. Importance is attached to the fact that with this apparatus the pores can be held open in this manner while the bars are being employed for pressing the secretions therefrom.

The preferred form of the invention has been set forth in the foregoing description; but I do not limit myself thereto, as I am aware that modifications may be made therein without departing from the spirit or sacrificing the advantages thereof, and I therefore reserve the right to make such changes as fairly fall within the scope of the claims.

What is claimed is—

1. In an apparatus of the character described the combination with a head and means for establishing suction therethrough; of intersecting cross-bars connected to the head in the line of suction and constituting rubbing devices.
2. In an apparatus of the character described the combination with a head, means for establishing suction therethrough, and

means for regulating the suction; of a frame fitted upon the head, and intersecting cross-bars secured within the frame and extending in the line of suction, said bars constituting 40 rubbing devices.

3. In an apparatus of the character described the combination with a recessed head; of a massage-frame surrounding the head adjacent the recessed face thereof, a flexible 45 covering upon the frame, cross-bars within the frame and intersecting the end of the recess, and means for establishing suction through the frame and recess.

4. In an apparatus of the character de- 50 scribed the combination with a recessed head; of a massage-frame surrounding the head adjacent the recessed face thereof, a flexible covering upon the frame, cross-bars within the frame and intersecting the end of the recess, means for establishing suction through the frame and recess, and spring-pressed 55 means under control of the operator for regulating the suction.

5. In an apparatus of the character de- 60 scribed the combination with a head, and means for establishing suction therethrough; of cross-bars connected to the head in the line of the suction and constituting rubbing devices.

In testimony that I claim the foregoing as my own I have hereto affixed my signature in the presence of two witnesses.

EDGAR M. FUNK.
